DESIGN.

—o—

J. L. FOLSON.

CARPET.

No. 17,211.

Patented Mar. 29, 1887.

UNITED STATES PATENT OFFICE.

JAMES L. FOLSOM, OF BROOKLYN, NEW YORK, ASSIGNOR TO THE HARTFORD CARPET COMPANY, OF HARTFORD, CONNECTICUT.

DESIGN FOR A CARPET.

SPECIFICATION forming part of Design No. 17,211, dated March 29, 1887.

Application filed February 25, 1887. Serial No. 228,893. Term of patent 3½ years.

To all whom it may concern:

Be it known that I, JAMES L. FOLSOM, a citizen of the United States, residing in Brooklyn, county of Kings, State of New York, have 5 invented a new and original Design for Carpets, of which the following is a specification, reference being had to the accompanying photograph, which forms a part of the same.

The invention relates to a design to be 10 worked into or upon surfaces, such as carpets or similar fabrics; and it consists in the novel configuration and grouping of figures herein specifically shown and claimed.

The accompanying photograph is a face 15 view of a carpet showing my new design.

The design consists of the figures or groups A, B, and C, as shown in the photograph.

The group A, found at the upper and lower 20 parts of the photograph, is a large cluster of flowers and leaves, having a large flower figure projecting below on the left; and below on the right a cluster of three smaller flowers projecting from between two flag-like leaves.

Above, on the right, is a leaf and fern spray 25 with small star-shaped flowers.

The group B, found at the right and left edges of the photograph, is similar in general

shape and size to the group A; but it has a large star-shaped flower below on the left and a similar one below on the right and a more 30 open leaf and flower cluster above on the left.

The group C, found in the center of the photograph, is a smaller group of flowers and leaves with projecting moss sprays. It is found substantially repeated in the group 35 shown at the four corners of the photograph.

What I claim as new, and desire to secure by Letters Patent, is—

1. The design for carpets, consisting of the group A, substantially as shown and de- 40 scribed.

2. The design for carpets, consisting of the group B, substantially as shown and de- scribed.

3. The design for carpets, consisting of the group C, substantially as shown and de- scribed.

4. The design for carpets, consisting of the groups A and B and the groups C, substan- tially as shown and described.

JAS. L. FOLSOM.
